ROSARY MEDAL

Raymond J. McMahon, 3185 Bellevue Ave., Apt. B-6,
Camillus, N.Y. 13219

Filed Nov. 23, 1970, Ser. No. 26,129

Term of patent 14 years

Int. Cl. D11—03

U.S. Cl. D45—16

FIG. 1

FIG. 1 is a face view of the obverse side of a rosary medal showing my new design; the back thereof is similar in appearance except that the cross has no corpus;

FIG. 2 is a top edge view thereof; and

FIG. 3 is a sectional view thereof taken on the line 3—3 of FIG. 1.

I claim:

The ornamental design for a rosary medal, as shown and described.
